PENCIL

Percy A. Sharow, Windsor, Ontario, Canada

Application September 26, 1935, Serial No. 42,196

15 Claims. (Cl. 120—18)

My invention relates to a new and useful improvement in a pencil of the floating type in which the writing point of the pencil may move inwardly and outwardly in response to the pressure exerted upon it so as to provide a yielding point which will relieve the writer of fatigue and cramps to a large extent.

It is an object of the present invention to provide a novel arrangement for adjusting the yieldable pressure which resists the inward movement of the writing point.

Another object of the invention is the provision of a pair of spring arms which operate as brakes in resisting the inward movement of the pencil and which may be adjusted to various degrees of pressure.

Another object of the invention is the provision of a pencil of this class in which yieldable means may be provided for resisting the outward movement of the writing point after the inward pressure has been released.

Other objects will appear hereinafter.

The invention consists in the combination and arrangement of parts hereinafter described and 25 claimed.

The invention will be best understood by a reference to the accompanying drawing which forms a part of this specification, and in which,

Fig. 1 is a side, elevational view of the invention.

Fig. 2 is a longitudinal, sectional view of the invention.

Fig. 3 is a sectional view taken on line 3—3 of Fig. 2.

35 Fig. 4 is a view taken on line 4—4 of Fig. 2.

Fig. 5 is a sectional view taken on line 5—5 of Fig. 2.

Fig. 6 is a sectional view taken on line 6—6 of Fig. 2.

40 As shown in the drawing, the invention comprises a barrel 9 which is closed at one end by the head 10 in which is formed the peripheral groove 11. Positioned in the barrel 9 is a disc 12, projecting outwardly from which are the hollow legs 13

45 which are diametrically positioned and project outwardly from the periphery of the disc 12. A stud 14 extends outwardly from one of the legs 13 and rides in a slot 15 formed in the barrel 9. Secured at their ends by a press fit in the head 10

50 are a pair of spring arms 16, each of which is provided with a head 17 adapted to engage the peripheral cone 18 which is fixedly mounted on the tube 19 which is internally threaded throughout the major portion of its length. This tube

55 is provided with a central bore 20 in its forward

part, in which the piece of lead 21 is positioned and held therein by frictional engagement with the bore 20.

The tube 19 projects through a central opening 22 formed in the disc 12 and through a neck 23 which projects from the disc 24. This disc is provided at opposite sides with peripherally-projecting lugs 25, each of which rides in a groove 26 formed in a sleeve 27, one end of which is crimped inwardly at 28 to engage in the groove 11. The neck 23 is threaded through a central opening formed in the head 10 and is adapted to engage the disc 12. Consequently, by rotating the sleeve 27, the member 24 is rotated and the neck 23 threaded inwardly or outwardly of the head 10, thus pressing the disc 12, when threaded in one direction, to compress the spring 29 which embraces the tube and engages at one end the disc 12 and at the opposite end the end of the cone 18. Threaded into the tube 19 is the follower 30 carrying at its inner or lower end the plunger rod 31 against which engages the end of the lead 21. The upper end of the follower 30 is provided with a cross-head 32, the ends of which ride in slots 33 formed in the tube 34 which is positioned centrally of the cylindrical extension 35. This cylindrical extension 35 is cut away as at 36 and the cut away portion is thrust into the sleeve 27 as a snug fit. The extension is provided with the lead-receiving chambers 37 in which extra pieces of lead may be positioned. An eraser 38 is secured to the upper end of the extension 35 and a cap 39 serves as a closure for this extension and for the eraser 38.

Threaded into the lower end of the barrel 9 is 35 the tapered head 40, the inner end of which is formed to provide the cone 41. Secured at one of their ends as a press fit in the end of the cone 18 and projecting axially therefrom, are the spring arms 42 and 43, each of which is provided with a 40 head 44. A spring 45 embraces the tube 19 and one end of this spring engages one end of the cone 18 and the other end of the spring engages the inner end of the cone 41.

Graduations 46 are formed on the end of the 45 sleeve 27 and an indicating mark 47 is displayed at a point on the upper end of the barrel 9. Graduations 48 along the side of slot 15 are adapted to cooperate with the angularly-turned end 49 of the stud 14.

In use when the device is assembled as illustrated in Fig. 2 and a lead 21 positioned in the bore 20, a rotating of the extension 35 relatively to the member 27 will effect a threading of the follower 30 inwardly of the tube 19 so that the 55

plunger 31 will force the lead to extend outwardly of the tube 19 the proper distance. When the pencil is used for writing, the pressure on the lead will cause the tube to move inwardly of the head 40 carrying with it the cone 18 and thus the inward movement will be against the compression of the spring 29 and also against the frictional contact of the heads 17 with the periphery of the cone 18. In order to adjust this resistance to inward movement, the user would rotate the member 27 relatively to the barrel 9. This would cause a threading of the neck 23 through the head 10 and move the disc 12 downwardly toward the point of the pencil, thus compressing the spring 19. Consequently, an increased resistance to inward movement would be encountered through the increased compression of the spring. Additional resistance would also be encountered because the spring arms would then be shortened as to their distance of flexing in as much as the legs 13 would move downwardly to the head bearing ends of the spring arms 17. This adjustment of the spring 29 and of the spring arms 46 would be indicated by the graduations 46 cooperating with the marker 47 and also would be indicated by the graduations 48 cooperating with the angularly-turned portion 49 of the stud 14. In this way a very delicate and proper adjustment of the resistance may be accomplished.

30 When the inward pressure on the pencil point is released its outward movement will be checked by the spring 45 and also by engagement of the heads 44 of the spring arms 42 and 43 with the cone 41. This will relieve the device of any sudden jars or shocks should the pencil be pressed upon a piece of paper, a desk or the like and suddenly removed therefrom. It is consequently seen that the pencil affords a means for adjusting the lead point to suit the individual requirements as some people desire a stiffer pencil than others and some press heavier on the paper than others.

While I have illustrated and described the preferred form of construction, I do not wish to limit myself to the precise details of structure shown, but desire to avail myself of such variations and modifications as may come within the scope of the appended claims.

Having thus described my invention, what I claim as new and desire to secure by Letters Patent is:

1. A pencil of the class described, comprising: a main body; a lead-receiving tube extending through said body and moveable longitudinally thereof; a pair of stationary spring arms on said body; and means fixedly mounted on said tube engageable with the ends of said spring arms for resisting inward movement of said tube relatively to said body.

60 2. A pencil of the class described, comprising: a main body; a lead-receiving tube extending through said body and moveable longitudinally thereof; a pair of stationary spring arms on said body; means fixedly mounted on said tube engageable with the ends of said spring arms for resisting inward movement of said tube relatively to said body; and means for adjusting the ends of said arms on said engagement means by adjusting the length of flexing of said arms.

70 3. A pencil of the class described, comprising: a main body; a lead-receiving tube extending through said body and moveable longitudinally thereof; a pair of stationary spring arms on said body; means fixedly mounted on said tube engageable with the ends of said spring arms for

resisting inward movement of said tube relatively to said body; means for adjusting the ends of said arms on said engagement means by adjusting the length of flexing of said arms; and additional resilient means for resisting inward movement of said tube relatively to said body.

4. A pencil of the class described, comprising: a body; a lead-receiving tube in said body and moveable longitudinally thereof; a pair of stationary spring arms on said body in spaced relation; an engagement member fixedly mounted on said tube and having an inclined surface adapted, upon inward movement of said tube relatively to said body, for engaging the ends of said arms and flexing the same outwardly, the resistance of said arms to outward flexing effecting a resistance to inward movement of said tube.

5. A pencil of the class described, comprising: a body; a lead-receiving tube in said body and moveable longitudinally thereof; a pair of stationary spring arms on said body in spaced relation; an engagement member fixedly mounted on said tube and having an inclined surface adapted, upon inward movement of said tube relatively to said body, for engaging the ends of said arms and flexing the same outwardly, the resistance of said arms to outward flexing effecting a resistance to inward movement of said tube; and means for adjusting the tension of said arms by regulating the length of flexing of the same.

6. A pencil of the class described, comprising: a main body; a lead-receiving tube extending in said body and moveable longitudinally thereof; a pair of spring arms, each fixed to said body at one of their ends; an engagement member having inclined surfaces adapted, upon inward movement of said tube, for engaging the free ends of said arms and flexing the same, the resistance of said arms to flexing movement effecting a resistance to inward movement of said tube.

7. A pencil of the class described, comprising: a main body; a lead-receiving tube extending in said body and moveable longitudinally thereof; a pair of spring arms, each fixed to said body at one of their ends; an engagement member having inclined surfaces adapted, upon inward movement of said tube, for engaging the free ends of said arms and flexing the same, the resistance of said arms to flexing movement effecting a resistance to inward movement of said tube; and a spring engaging said engagement member for further resisting inward movement of said tube.

8. A pencil of the class described, comprising: a main body; a lead-receiving tube extending in said body and moveable longitudinally thereof; a pair of spring arms, each fixed to said body at one of their ends; an engagement member having inclined surfaces adapted, upon inward movement of said tube, for engaging the free ends of said arms and flexing the same, the resistance of said arms to flexing movement effecting a resistance to inward movement of said tube; a spring engaging said engagement member for further resisting inward movement of said tube; and means for simultaneously adjusting the tension of said spring and of said spring arms.

9. A pencil of the class described, comprising: a main body; a lead-receiving tube extending in said body and moveable longitudinally thereof; a pair of spring arms, each fixed to said body at one of their ends; an engagement member having inclined surfaces adapted, upon inward movement of said tube, for engaging the free ends of said arms and flexing the same, the resistance of said arms to flexing movement effecting a resistance to inward movement of said tube; and means for simultaneously adjusting the tension of said spring and of said spring arms.

ends of said arms and flexing the same, the resistance of said arms to flexing movement effecting a resistance to inward movement of said tube; a spring engaging said engagement member for further resisting inward movement of said tube; means for simultaneously adjusting the tension of said spring and of said spring arms; and means for checking the outward movement of said tube after release of the pressure forcing the same inwardly.

10 10. A pencil of the class described, comprising: an elongated body; a lead-receiving tube extending through said body and slidably longitudinally thereof; a stationary head on said body having inclined surfaces; an engagement member mounted fixedly on said tube; a pair of spring arms fixed at one end to one end of said engagement member and extending axially therefrom, said head having an inclined surface adapted for engaging the free end of said spring arms and checking outward movement of said tube relatively to said body.

15 11. A pencil of the class described, comprising: an elongated body; a lead-receiving tube extending through said body and slidably longitudinally thereof; a stationary head on said body having inclined surfaces; an engagement member mounted fixedly on said tube; a pair of spring arms fixed at one end to one end of said engagement member and extending axially therefrom, said head having an inclined surface adapted for engaging the free end of said spring arms and checking outward movement of said tube relatively to said body; and a spring engaging

said head and engaging said engagement member for assisting in checking outward movement of said tube relatively to said body.

12. A pencil of the class described, comprising: a main body; a lead-receiving tube extending in said body and movable longitudinally thereof; means in said body moveable simultaneously with said tube; and yieldable friction means engaging said last named means for resisting inward movement of said tube.

10 13. A pencil of the class described, comprising: a main body; a lead-receiving tube extending in said body and moveable longitudinally thereof; means in said body moveable simultaneously with said tube; yieldable friction means engaging said last named means for resisting inward movement of said tube; and resilient means for forcing said tube outwardly upon release of the inwardly directed pressure on said tube.

15 14. A pencil of the class described, comprising: a main body; a tube extended slidably in said body; means mounted on said tube and moveable in unison therewith; and yieldable means contacting and slidable on said last named means for resisting inward movement of said tube.

20 15. A pencil, comprising: a main body; a lead-receiving tube projected into and slidably longitudinally of said body; an engagement member mounted on said tube; and yieldable means frictionally engaging said engagement member and slidable thereon for resisting inward movement of said tube.
